UNITED STATES PATENT OFFICE.

EDWARD L. TROUP, OF WAUSEON, OHIO.

SEGMENTAL GEAR-WHEEL.

No. 826,129.

Specification of Letters Patent.

Patented July 17, 1906.

Application filed November 16, 1905. Serial No. 287,589.

To all whom it may concern:

Be it known that I, EDWARD L. TROUP, a citizen of the United States, and a resident of Wauseon, in the county of Fulton and State 5 of Ohio, have invented a new and useful Improvement in Segmental Gear-Wheels, of which the following is a specification.

My invention relates to a segmental gear-wheel.

10 In gear-wheels having cogs integral with the body of wheel the loss of one cog renders the entire wheel useless and stops the operation of the mechanism of which it forms a part until the wheel can be removed and replaced. The removal of a broken gear-wheel often involves the dismemberment of a machine at great expense of labor and loss of time and when such breakage occurs in car-motors at great inconvenience to the public.

15 The object of my invention is to provide a strong and durable gear-wheel the cogs of which are readily attached and detached in segments without the removal of the main body portion of the wheel from the shaft on which it is mounted or the detachment of the 20 shaft from the body of the machine or mechanism of which it forms a part. I accomplish these objects by constructing a gear-wheel in parts adapted to be assembled and 25 locked together, as hereinafter described, and illustrated in the drawings, in which—

Figure 1 is a side elevation of a gear-wheel constructed in accordance with my invention, showing the lock-disk partly broken 30 away and cog-segments removed. Fig. 2 is a diametric section of the wheel complete on line $x-x$ of Fig. 1; and Fig. 3 is a similar section of the main body portion of the wheel, 35 partly broken away, with the cog-segments and lock-disk removed.

In the drawings, 1 represents the main body portion of a gear-wheel constructed in accordance with my invention, which is provided with an integral hub 2, having the outwardly-threaded projecting portion 3 and a bore 4 of suitable diameter for the shaft 5, on which it is to be fixedly mounted. The body portion 1 is also provided with a rim 6, that is integral with a web 7 of the hub and 40 concentric to the bore 4, forming a cog-base 8 and a retaining-flange 9, the flange forming a shoulder 10 at one side of the cog-base. The shoulder 10 has formed therein the lateral 45 annular groove 11, the inner side 12 of which 50 forms an extension of the cog-base into the flange 9, and the outer side 13 of the groove

is preferably beveled inward toward the base from the face of the shoulder 10. The cog-base has formed therein at diametric points transverse grooves 14, in which are mounted 60 the stops 15, having portions projecting above the cog-base and radial thereto a less distance than the flange 9.

Upon the cog-base of the body portion 1 there is mounted an annular cog-rim 16 of 65 uniform radial thickness, the inner face of which is adapted to closely fit around the cog-base. The cog-rim 16 is of a radial thickness greater than the radial projection of the flange 9 of the body portion 1 of the wheel 70 and has formed concentric around its inner portion on each side a rabbeted concentric groove 17 and a tongue-flange 18. The cog-rim 16 has formed in its outer circumferential portion at equal intervals the cogs 19 of 75 equal depth and pitch, and the rim is radially divided into segments 20 of any desired length of arc, the divisions being made midway between two cogs, as shown in Fig. 1.

21 represents a locking-disk having a central hub 22, bored and internally threaded to run on the threaded portion 3 of the hub 2 of the main body portion 1, a recessed web 23, and a thickened rim portion 24, rabbeted on its inner face to form the circumferential shoulder 25, the side shoulder 26, and the annular groove 27. The rim-face 28 of the disk is of a diameter equal to the diameter of the rim-face 28' of the flange 8 of the body portion 1, and the groove 27 is 80 opposite the groove 11 in the flange 9 and is of equal size, shape, and depth, and each are adapted to receive one of the tongue-flanges 18 of the cog-rim segments 20, while the opposite grooves 17 of the cog-rim are adapted 85 to receive the tongue-flanges 29 of the flange 9 and the rim 24, formed by the grooves 11 and 27. The outer circumferential faces of the tongue-flanges 18 are beveled to coincide with the beveled face 13 of the tongue-flanges 29 of the flange 9, and the disk-rim 24 and the inner circumferential shoulders 30 and 30' of the cog-segments, which are formed 90 by the rabbeted grooves 17, are adapted to coincide with the rim-faces 28 and 28' of the disk-rim 24 and the flange 9, respectively, and rest thereon as a base. The cog-segments 20, which abut at the stops 15, have incuts 31 to receive the projecting portion 95 of the stops, whereby the cog-segments are shouldered against the stops and prevented 100 from turning on the cog-base of the main

9485 9490 9495 9500 9505 9510 9515 9520 9525 9530 9535 9540 9545 9550 9555 9560 9565 9570 9575 9580 9585 9590 9595 9600 9605 9610 9615 9620 9625 9630 9635 9640 9645 9650 9655 9660 9665 9670 9675 9680 9685 9690 9695 9700 9705 9710 9715 9720 9725 9730 9735 9740 9745 9750 9755 976

body portion 1 of the wheel, and the hub 2 is provided with the grooves 32 to receive the spline or feather 33 of the shaft 5. Thus constructed the parts of the wheel are assembled and locked together as a whole by first assembling the cog-segments around the cog-base of the main body portion of the wheel, with the tongue-flanges 18 of one side of each segment in the groove 11 of the flange 9 and the tongue 29 of the flange 9 in the adjacent groove 17 of the cog-segments and with the segments having the incuts 31 abutting the stops 15. The locking-disk 21 is then run on the threaded portion 3 of the hub 2 of the main body portion 1 by a wrench, which is adapted to engage the disk by means of the apertures 34, provided in the web 23, until the shoulder 26 abuts the cog-base and the tongue-flanges 18 and 29 are in their respective opposite grooves 27 and 17. In this position the cog-segments are securely locked and held firmly seated around the cog-base and between the disk 21 and the flange 9 by the interlocking tongues 18 of the segments extending into the opposite grooves 11 and 27, respectively, of the flange 9 and the disk 21, and by the tongues 29 of the flange 9 and the disk 21, extending into the grooves 17 of the cog-segments, with the outer sides of the flange 9 and the rim 24 of the disk flush with the sides of the outer portion of the cog-segments. It is apparent that when the parts are so locked together by the disk 23 there will be no tendency in the operation of the wheel to unscrew the disk 23 from the threaded portion 3 of the hub 2, as the cog-segments being locked against circumferential movement on the cog-base of the main body portion power applied to the cog-segments can have no effect to either tighten or loosen the disk, and it is also apparent that the disk may be loosened for the removal of a broken segment and the substitution of a new one without removing the body of the wheel or the disk from the shaft and without disturbing the other segments or having to remove the shaft.

To facilitate the tightening or loosening of the disk 23, the web of the body portion 1 of the wheel may be provided with the apertures 35, as shown in Fig. 3, for the application of the wrench thereto in opposition to a wrench similarly applied to the disk.

55 What I claim to be new is—

1. In a segmental gear-wheel, the combination of a main body portion having a hub provided with an externally-threaded end portion, and with a concentric rim adapted for a cog-base, said rim being provided with a grooved shoulder-flange at one side, a locking-disk having a grooved rim adapted to shoulder against the cog-base rim on the opposite side, and a hub axial to the disk that

is internally threaded and adapted to be run 65 on the threaded portion of the hub of the main body portion, and cogged segments adapted to be mounted on the cog-base rim and together form a complete cogged rim around the base, concentric thereto, said segments being provided on their opposite sides with flanges and grooves respectively complementary to the grooved flange of the body portion and the rim of the disk, and adapted to be interlocked therewith, and secured thereby, around and upon the cog-base rim, when the disk is run on the hub of the body portion until shouldered against the cog-base rim, and means to lock the segments against movement around the cog-base rim, substantially 80 as set forth.

2. In a segmental gear-wheel, the combination of a main body portion having an integral hub provided with an externally-threaded end portion, and with a cog-base 85 rim that is concentric to the hub and provided with a grooved shoulder-flange at one side, and with transverse grooves, radial stops secured in the transverse grooves, a locking-disk having a hub internally threaded and 90 adapted to be run on the threaded end of the hub of the main body portion, and provided with a rim having a groove opposite to the groove of the shoulder-flange of the cog-base rim, cogged segments adapted together to 95 form a cogged rim around the cog-base rim, the segments being provided with incuts adapting them to shoulder against the radial stops, and having side flanges complementary to the grooves of the shoulder-flange and 100 the rim of the locking-disk, and to extend into the grooves of the shoulder-flange and the disk-rim when the disk is run onto the hub of the body portion until it is compressed on the cog-base rim substantially as set forth. 105

3. A segmental gear-wheel comprising a main body portion provided with a hub having an exteriorly-threaded end portion, and a cog-base rim concentric to the hub and integrally connected therewith by a web, said 110 rim having transverse grooves, and being provided with a concentric flange forming a shoulder at one side of the cog-base rim that is provided with a lateral annular groove extending the cog-base, radial stops mounted in 115 the transverse grooves, cogged segments mounted on the cog-base, and forming a complete rim around and coinciding with the cog-base and having incuts to receive the radial stops, and side rabbets and grooves forming 120 annular tongue-flanges around the base portion of the cogged rim, and a locking-disk having a central hub bored and internally threaded to run on the threaded portion of the hub of the main body portion, and a rim rabbeted 125 and grooved complementary to the cog-base rim, and the segments, and adapted to interlock the segments between and with the disk-

rim and the shoulder-flange of the cog-base rim when the disk is run in on the hub of the main body portion.

4. In a segmental gear-wheel, the combination of a main body portion having a hub extension externally threaded, and a concentric cog-base rim that is provided with a shoulder-flange, a locking-disk provided with an internally-threaded hub adapted to be run on to the hub extension of the main body portion, and a rim concentric to the hub having a diameter equal to the diameter of the shoulder-flange, and cogged segments adapted to fit around and to form a complete cogged rim around the cog-base rim, the segments, the shoulder-flange, and the disk-rim, being

provided with complementary interlocking means adapting the segments to be interlocked between the shoulder-flange and the rim of the disk when the disk is run on to the hub of the main body portion, and the cog-base rim being provided with transverse radial stops, and the segments with incuts to receive the stops. 20

In witness whereof I have hereunto signed 25 my name, in the presence of two subscribing witnesses, this 10th day of November, 1905.

EDWARD L. TROUP.
